UNITED STATES PATENT OFFICE

157,398

COFFEE-MAKING DEVICE

Joseph S. Mather, Jr., Toledo, Ohio

Application October 23, 1947, Serial No. 142,102

Term of patent 14 years

(Cl. D44—26)

To all whom it may concern:

Be it known that I, Joseph S. Mather, Jr., a citizen of the United States of America, residing at Toledo, county of Lucas, and State of Ohio, have invented a new, original, and ornamental Design for Coffee Making Device, of which the following is a specification, reference being had to the accompanying drawings forming part thereof.

Figure 1 is a side elevational view of a coffee making device showing my new design.

Figure 2 is a top plan view of the apparatus, and

Figure 3 is a near elevational view thereof.

The dominant features of the design reside in the parts shown in full lines.

I claim:

The ornamental design for a coffee making device, substantially as shown and described.

JOSEPH S. MATHER, JR.
